UNITED STATES PATENT OFFICE

111,689

DESIGN FOR A VACUUM CLEANER

Lloyd B. Salt, Chestnut Hill, Mass., assignor to
B. F. Sturtevant Company, Hyde Park, Boston,
Mass.

Application July 21, 1938, Serial No. 78,642

Term of patent 7 years

To all whom it may concern:

Be it known that I, Lloyd B. Salt, a citizen of the United States, residing at 37 Woodman Road, Chestnut Hill, in the county of Suffolk and State of Massachusetts, have invented a new, original, and ornamental Design for a Vacuum Cleaner, of which the following is a specification, reference being had to the accompanying drawing constituting a part thereof.

Fig. 1 is a front elevational view of a vacuum cleaner showing my new design;

Fig. 2 is a side elevational view;

Fig. 3 is a sectional view along the lines 3—3 of Fig. 2, and

Fig. 4 is a rear elevational view.

The dust bag shown in dotted outline in Fig. 2 is omitted from Figs. 1, 3 and 4, for convenience of illustration.

I claim:

The ornamental design for a vacuum cleaner, substantially as shown and described.

LLOYD B. SALT.
